UNITED STATES PATENT OFFICE.

OREN J. FAIRCHILD, OF PASADENA, CALIFORNIA.

AUTOMATIC BOWLING MECHANISM.

1,375,835.

Specification of Letters Patent. Patented Apr. 26, 1921.

Application filed December 14, 1917. Serial No. 209,175.

To all whom it may concern:

Be it known that I, OREN J. FAIRCHILD, a citizen of the United States, and a resident of Pasadena, in the county of Los Angeles 5 and State of California, have invented certain new and useful Improvements in Automatic Bowling Mechanism, of which the following is a specification.

My invention relates to bowling alleys 10 and mechanism employed in connection therewith, the principal object of which is to provide automatic mechanism for collecting and setting the bowling pins and the balls after each play without any manual attention whatever.

In all bowling alleys the pins, ten in number, are arranged symmetrically in triangular form around a central pin, one corner or angle of the triangle being in the exact 20 center of the alley and facing the players and the other two angles being oppositely disposed laterally of the alley. Thus transversely of the alley would be four lines of pins with a single pin in the front line, two pins in the second, three in the third and four pins in the fourth and rear line, the pins in the several lines being staggered 25 with respect to each other and the central pin in the third line being the center of the 30 imaginary circular lines about which all of the other pins are arranged. Hence, the two pins in the second line, the two outer pins of the third line and the two innermost pins of the rear line are concentrically arranged 35 about the central pin at angles of 60 degrees, and the corner pins of the triangle are arranged about the same axis in a larger circle and spaced at angles of 120 degrees.

In order to properly set forth the objects 40 of my invention and describe the mechanism employed for carrying out the said objects, I have divided the set of ten pins into three separate classes, namely, the central, concentric and corner pins of the triangle, and 45 advantage is taken of the concentric arrangement of the majority of the pins for collecting and subsequently setting all of the pins of the set. Another object, therefore, is to provide means for collecting all of the set, 50 after a play is completed, in concentric order about the axis of the triangle and on the circle of the six concentric pins, and for subsequently moving the central and corner pins of the triangle into their respective

playing positions with the normally concentric pins. 55

A further object is to provide means for collecting and automatically setting any number less than the whole number of the pins which may have been knocked down in 60 a play, without in any manner disturbing or displacing the other pins.

A still further object is to provide means for conveying the displaced pins, usually termed "deadwood," from the alley to a 65 point immediately below the alley, for collecting and setting the pins beneath the alley and for simultaneously raising all or any number of the displaced pins through the 70 floor of the alley and properly spacing and depositing the same thereupon for another play.

Another object is to provide selector means capable of automatic operation, whereby the operation of the pin setting mechanism 75 may not be interrupted when one or more of the pins may have been left in playing position on the alley floor previous to the setting operation, and by means of which the remaining pins may be collected and properly set as usual. 80

Another object is to provide a movable alley floor section for receiving and holding the pins in playing position and capable of being raised and inclined for discharging 85 the upset pins therefrom after a play, without disturbing the pins left standing.

Another object is to provide a pin conveyer for receiving the pins discharged from the floor after a play, *en masse* or singly, by 90 means of which the pins may be turned and conveyed in single file and all facing in the same direction, to the pin setting mechanism, after having been elevated to setting position, cups being provided for receiving 95 the pins at such elevated positions, and means being provided for elevating the pins further into playing position above the floor.

Another object is to provide means for applying power to the conveyer and setting mechanism, intermittently as needed, by a system of electrically actuated clutches controlled by manually operated switches at the player's end of the alley, and for collecting 100 and returning the used balls to their normal 105 positions near the players. Other objects will appear as the description progresses.

In the accompanying drawings I have illustrated a preferred embodiment of my invention, but it will be obvious that the details of structure shown may be substantially changed within the scope of the appended claims, without departing from the spirit or enlarging the scope of my invention.

With particular reference to the said drawings, in which similar characters of reference are employed for indicating the same or like parts as mentioned in the description hereinafter following, it will be noted that in the assembled views of my invention numerous parts are of necessity omitted from each of the views for clarity of illustration and each of the assembled views is depended upon to show only a certain portion of the invention and the relation thereof to other parts of the mechanism, while the detail views clearly show all of the parts in their operative relation.

I will now describe the views of my mechanism as illustrated in the drawings:

Figure 1 is a top plan view of one and portions of two adjacent bowling alleys showing my improved mechanism in connection therewith.

Fig. 2 is a plan of my mechanism with the floor removed and certain other portions omitted for clarity of illustration.

Fig. 3 is a plan of the upper end of the pin elevating cage.

Fig. 4 is a plan of the pin elevating cage with the top plate thereof removed and showing clearly the pin elevator.

Fig. 5 is a plan of the pin elevator cage base and certain elements therebeneath.

Fig. 6 is a plan of the pit and cage base of one of the alleys showing particularly the selector mechanism and related elements.

Fig. 7 is an enlarged side elevation of the pin elevator cage controlling latch.

Fig. 8 is an enlarged side elevation of one of the selector magnets and a portion of the pin elevator.

Fig. 9 is an end of the said magnet and an armature therefor, and Fig. 10 is a fragmentary view of the opposite end of the magnet.

Fig. 11 is a longitudinal sectional elevation of one of the alleys and the mechanism thereof.

Fig. 12 is a transverse sectional elevation of a portion of the mechanism shown in Fig. 11 taken on a plane forward of the pins; and Fig. 13 is a longitudinal section of one of the side ball and pin channels in one of the alleys.

Fig. 14 is a longitudinal section of one of the alleys showing the movable floor and the lifting means therefor; Figs. 15 and 16 are detail views of the cable connectors with the floor lifting rods.

Fig. 17 is a plan of the pin conveyer and elevator, and the ball elevator at the rear of the alleys, showing the mechanism for one alley complete and portions of the mechanism for the two adjacent alleys.

Fig. 18 is an end elevation of the power clutch magnet for the pin and ball elevators and cage operating mechanism.

Fig. 19 is a cross sectional elevation of the mechanism shown in Fig. 17, looking rearwardly of the alley.

Fig. 20 is a longitudinal section of the mechanism shown in Fig. 17.

Figs. 20^a and 20^b, are respectively, a plan and an elevation of the pin elevating means for the elevator.

Fig. 21 is an enlarged sectional view of the lower end of the pin elevator cage.

Fig. 22 is a fragmentary plan of the same and Fig. 23 is an elevation of one of the pin receiving cups and support therefor mounted on the cage.

Fig. 24 is a side elevation of one of the pin swings for moving the pins from filling to setting position-used only for the corner and central pins of the set. Fig. 25 is an end elevation of the same; Fig. 26 is a side elevation of the swing latch means shown in an opposite position from that shown in Fig. 24; Fig. 27 is a plan of one of the swings and a portion of the elevator cage; Figs. 28, 29 and 30 are detail views of the pin swing latch actuating arms and rollers; Fig. 31 is a substantially enlarged view of the lower portion of one of the swings and mounting therefor; and Fig. 32 is a fragmentary section of the cage elevator showing a pin lifting element seated thereon.

Fig. 33 is a fragmentary elevation, looking rearwardly of the alley, of the upper end of the ball elevating means.

Fig. 34 is a sectional elevation of the ball elevator driving shaft and clutch means therefor; Fig. 35 is a transverse section of one of the clutches shown in Fig. 34.

Fig. 36 is a sectional elevation of the pin elevator cage base and pivoted support therefor, showing the cage operating and elevator lifting gears.

Fig. 37 is a sectional elevation and detail of the magnetic switch actuating mechanism for controlling the operation of the cage; Fig. 38 is an end elevation of the same, and Fig. 39 is a fragmentary plan of the same.

Fig. 40 is a substantially enlarged sectional elevation of a portion of the cage frame and movable floor support showing one of the pins about to be lifted upwardly through the trap door in the frame opening and floor to setting positions; Fig. 41 is a section of the same showing the pin partially extended through the opening in the floor and with the trap doors raised to permit the passage of the pin therethrough; Fig. 42 is a similar section of the same showing

ing the pin finally seated upon the floor or the alley and with the pin elevating means retracted and the trap doors closed. Figs. 43 and 44 are, respectively, fragmentary views showing a partial plan of one of the frames around one of the pin openings and a side elevation of the door hinges. Fig. 45 is a sectional view of the frame and opening therein showing electrical contacts by means of which the elevation of a pin for this opening is controlled.

Fig. 46 is an enlarged plan view, partly in section, of the alley floor lifting means, clutches for imparting motion thereto and other driven parts of the mechanism. Fig. 47 is a side elevation of the same and Fig. 48 is a sectional elevation of the same showing the differential floor lifting elements.

Fig. 49 is a plan view of the starting clutch and actuating mechanism therefor, for controlling the application of power to the elements shown in Figs. 46, 47 and 48; Fig. 50 is a side elevation of the same; Figs. 51 and 52 are, respectively, front and rear elevations thereof, and Fig. 53 is a transverse view of one of the driving shafts showing a form of jaw clutch.

Fig. 54 is a plan view of a duplex clutch and actuating means therefor, for applying power to the floor lifting means and pin and ball elevating elements; Fig. 55 is a side elevation of the same; Fig. 56 is an end elevation thereof, and Fig. 57 is an end elevation of the clutch support therefor.

Fig. 58 is a circuit diagram of the electrical connections for the various elements of my improved system.

I will now clearly describe the operation and structure of a preferred embodiment of my invention as disclosed in the drawings hereinbefore described, and in order to thoroughly comprehend my system of automatically handling the pins and balls, it will be necessary to bear in mind the classification of the pins as hereinbefore set forth, the central or axis pin or the position therefor being represented on the drawings as A, the pin and position of the concentric pins as B, and the corner or triangularly related pins and positions as C; separate devices being employed for collecting and elevating these differently positioned pins, which will, in turn be separately described.

The bowling alleys in which my mechanism is placed for operation may be of the usual character and formation, one or more alleys being equipped for operation by means of my automatic system, as may be desired, by a duplication of the mechanism shown, but only the mechanism employed in a single alley will be described.

The alleys 1 are provided with a movable floor section 2 of rectangular formation, substantially larger than a square or rectangle which will clear the area of the pin

triangle, and suitably supported on one or more transverse rails 3. A metal frame 4 is also supported rigidly on the rails 3 and is provided with a plurality of openings 5 which correspond in number and position 70 to the playing positions of the pins A B or C, said openings being enough larger than the pins to permit the passage of the pins therethrough, as will be hereinafter described. The walls of the openings 5 are 75 substantially extended above and below the ribs of the frame which connect the same to afford rigidity, and the upper edges of the walls of these openings are preferably beveled, as shown in Fig. 41, so that the 80 beveled surfaces of openings 6 formed in the floor 2, through which the pins may pass, may seat readily upon the upper edges of the frame.

Immediately beneath the frame 4 and floor 85 2, a pin elevating cage is positioned concentrically with the position A of the central pin, and this cage comprises a top plate 7 and a bottom plate 8 which are spaced apart and held together by means of a plurality 90 of tubes 9 suitably attached at the top and bottom ends to the plates, there being three of said tubes shown and employed in the present invention. The cage is revolvably supported on a base 10 which may be mounted on a suitable pier below the alley, or otherwise, a relatively larger spur gear 11 and a removably held sprocket gear 12 being loosely mounted on a pivot pin 13 attached to the bottom cage plate 8 and suitable anti-friction ball or roller bearings being provided at the base and bottom cage plate for obvious purposes. An upwardly extended pin 13' Fig. 36 is provided on the sprocket 12 for engagement with a similar depending 105 pin 13'' on the bottom of gear 11, so that the operation of sprocket 12 will effect the rotation of gear 11 when the pins 13 and 13' are engaged and not otherwise.

A plurality of concentrically arranged 110 rollers 14 are rotatably held on the upper surface of the top cage plate 7 and engage an annular flange 15 which depends from the stationary frame 4 and is concentric with the central pin position A, thus serving to 115 center the cage with the pins and support the same at the upper end. Each of the spacing tubes 9 of the cage has a spindle 16 extending therethrough and respectively above the upper surface of top plate 7 and 120 below the bottom plate 8 of the cage, a small driven gear 17 being fixed to the lower end of each of said spindles and meshing with the larger central driving gear 11. The upper end of each of said spindles carries a 125 pair of drums, 18 and 19, (Figs. 3 and 11) of, respectively, large and small diameter and these drums are adapted to be rotated with the gears 17 on the lower ends of the spindles, for purposes hereinafter described. 130

The bottom plate 8 of the cage has three substantially elongated arms 20 (Figs. 4, 6 and 22) which register normally with the corner pin positions C, six relatively shorter arms 21 which register normally with the concentric pin positions B and a single arm 22 which extends longitudinally outward from the central pin position A. A ring like pin elevator body 23 (Figs. 4, 12 and 21) 10 is slidably held above the bottom cage plate 8 on the spacing tubes 9, the tubes extending through lugs 25' on the interior of the body and arms 24 project outwardly from the body over the arms 20 of the plate 8, the 15 ring like portion of the elevator being wholly within the circle of the concentric pin positions B and yet relatively close thereto, and the outer ends of the arms 24 being slightly enlarged and terminating at 20 points inwardly of the corner pin positions C.

The top plate 7 of the cage carries three small sheaves 25, as shown in Fig. 3, over which cables 25' extend and are connected 25 at one end to the small drums 19, while the other ends of these cables extend outwardly into the cage for connection with a latch mechanism to be hereinafter described. Three larger sheaves 26 are also carried on 30 the top plate 7 and carry cables 26' which lead to the large drums 18 and are suitably connected therewith at one end of their ends. The lower ends of cables 26' extend downwardly into the cage and are attached to 35 lugs or pins 27 extending outwardly from the elevator ring, thus suspending the elevator within the cage and between the top and bottom plates thereof on the cables 26' for movement upwardly and downwardly 40 over the guide and spacing tubes 9. It will be obvious from the description above, that in the event of the cage being stopped from rotation, the sprocket 12 below the cage will drive the gear 11 by the means shown, and 45 gear 11 will drive small gears 17, spindles 16 and drums 18 and 19, thereby winding the cables 25' on the drums 19 and 18, respectively, unwinding the cables 26' from the drums, and vice versa, for raising and lowering the elevator body relative to the top of 50 the cage, for purposes hereinafter described. When the cage is free to turn, however, the weight of the elevator thereupon will suffice to permit the rotation of the cage without 55 serving to raise the elevator.

A plurality of cups are mounted on the bottom plate 8 of the cage for receiving the pins at what is hereinafter termed the "filling" positions, a single cup *a* being provided 60 for the central pin A, six cups *b* being provided for the concentric pins B and three cups *c* being provided for the corner pins C, all of said cups being substantially similar in form and of an equal size and conforming 65 to the contour of the base of a pin, but being

differently supported. (See Figs. 21, 22 and 23).

Cups *b* are rigidly mounted on bottom plate 8 of the cage by means of a pair of tubular supports *b'* which may be suitably 70 attached at opposite ends to the cups and cage plate 8, the cups being held at a uniform height above the cage plate and in the planes of the pin positions B. Plungers *b''* 75 are slidably disposed in the tubes *b'* and are bent around at the bottom so as to form horizontal portions below the bottom surface of plate 8, and above and within the interior of cups *b* flat disks *b'* may be attached to the upper ends of the plungers, as 80 shown in Fig. 21, and enough space provided between these disks and the bottom of the cups to permit the depression of the upper disks when a pin is delivered to a cup and the lifting of the plungers and disks again 85 after the removal of a pin from a cup.

Figs. 6 and 7 show a means positioned beneath the cage plate 8 for lifting the cage releasing means, namely the plungers *b''* 90 within the tubes *b'*, which consists of a latch 28 having a curved free end 28' disposed in the path of the bottoms of said plungers and is pivotally supported on a skeleton base member 29, a weight 30 being provided on the outer end of the latch for normally 95 holding the free end thereof upwardly in the path of the releasing means. A projection 30' on the free end of the latch is adapted to engage pins *b* depending from the arms 21 of the plate 8, so that in the event that a cup *b* has no pin therein when the cup reaches a point above the latch, the edge of the projection 30' on the latch will be engaged by the pin *b* on the cage plate arm 21 and thus stop the rotation of the cage 100 while a pin is being delivered to the cup *b*. When a pin is deposited in the cup *b*, however, the latch will be forced downwardly so as to disengage the end thereof from the pin *b* and the rotation of the cage may proceed. 105

The cups *c* for the corner pins C are pivotally mounted on swings which are movable in both directions between the filling and setting positions. That is they are movably disposed between the circular lines of the corner and concentric pins and positions B and C, these swings being pivoted at points midway of the two circles. The swings, three in number, comprise a pair 115 of parallel bars 31 pivoted to each of the opposite sides of the cups *c* at their upper ends and pivotally supported at their lower ends on bearings 32 which are attached by suitable means to the arms 20 of the bottom 120 cage plate 8, the arms 20 at such points being substantially widened so as to provide space between the bearings 32 for the elevator arms 24, and the outer member of one pair 125 of said parallel bars being extended at its 130

lower end 33 to a point substantially below the cage plate 8, as shown in Fig. 24. The parallel bars of each swing are braced laterally by means of braces 34 riveted to the bars at their upwardly bent ends and suitably secured at their lower horizontal portions to the pivot pins 35. A latch is provided for each of the corner pin cup swings which consists of a slidable frame member 36 provided with a horizontally elongated slot 36' through which the extended ends of the pivot pins 35 project. A link 37 which is pivoted at the inner end to a depending extension 37' on member 36 and has a slot 38 through which a pin 38' attached to the end 33 of swing bar 31 is extended, the link 37 being adapted to move horizontally over pin 38'. A swing actuating arm 39 is pivoted at its inner end to an upwardly projecting extension 39' on member 36 and a frame locking lever 40 which is pivoted to the outer end of member 36 and has a pair of shoulders 40' and 40'' is adapted to engage the outer end of pin 35 extending through the slot 36'. Lever 40 (Figs. 24 and 26) has a depending arm 41 to which a roller 41' is attached by means of a stem 42 (Figs. 28 and 30), the upper end of which stem is clamped to the arm 41 by means of a stud or bolt 42', the rollers on each of the levers 40 being extended below the cage plate 8 substantially so as to clear the latch mechanism and for engagement with and operation by a set of cams 43 attached to the skeleton base 29 by means of arms 44. The roller 41' and cam 43 of each swing unit occupies a different plane and the rollers may be of different diameter so as not to interfere with those of another unit. The inner ends of the latch frame members 36 have cables 45 attached thereto which run inwardly over pulleys 46 suitably mounted on the cage plate 8 and are attached to the lower ends of the coil springs 47, the upper ends of said springs being attached to the lower ends of the cables 25', as shown in Figs. 11 and 24. A bell crank 48 is pivotally supported on the cage plate 8 and is connected by means of its lower arm and a rod 49 with the stud 42' of lever 40, and the other arm of each bell crank is adapted to be depressed by means of a bent rod 50 which depends from the elevator arm 24.

55 The pin setting position of the swing is shown in broken lines in Fig. 24 with the cup *c* below the position C of the triangle and in full lines in Fig. 26. The elevator having been previously raised for the pin setting operation and thus entirely relieved the tension on spring 47 by the unwinding of the cable 25' on its drum on plate 7 of the cage, and thereby having permitted the latch frame 36 to be moved to its outward

60 extreme of action by means of a spring 54

which is attached at opposite ends to the rear or inner end of the frame and the outer end of pin 35 in extended bar 31 of the swing, and the shoulder 40' of latch lever 40 having engaged the pin 35.

The descent of the elevator will renew the tension on spring 47 by the winding of the cable 25' on its drum on plate 7 of the cage and when the elevator reaches its downward limit of action, the depending rod 50 thereon depresses the upper arm of the bell crank 48 and disengages the shoulder 40' from pin 35 by means of its connection with the bell crank 48 by means of rod 49, thus permitting a movement of the frame 36 inwardly until 75 it is arrested by the engagement of the shoulder 40'' with the pin 35, as shown in Fig. 24.

In the movement of the frame 36 as above described, the swing actuating arm 39, by 85 means of the engagement of a pin 52 extended from the bar 31 and a notch 51, has moved the swing from the position shown in Fig. 26 to that shown in Fig. 24, and the notch therein, after the completion of 90 the movement referred to, has been disengaged from pin 52 by means of another pin 53 in bar 31 which engages the end of the arm 39, this pin moving in an arc with the movement of the swing.

The inward movement of the frame 36 which carries link 37 therewith and the outward movement of pin 38' in the slot 38 of this link moves the several parts of the latch to a contact position such that a further inward movement of frame 36 must result in a reverse action of the swing, thus moving the same to the setting position shown in broken lines.

In the positions shown in Fig. 24, thus 105 further movement of frame 36 is prevented by the engagement of the shoulder 40'' of the frame latching lever 40 with pin 35. Thus locked in filling position the swing remains stationary while the cage nearly 110 completes its revolution, whereupon the rollers 41' of the three latches 40, 40, 40 attached to their respective frames 36, 36, 36, each roller being adjusted to a different practical plane, move into contact with their respective cams 43, 43, 43 which are in corresponding planes to the rollers, and the cams serve to move the rollers inwardly and thus disengage the shoulders 40'', 40'', 40'', on latches 40, 40, 40 from their pins 35, 35, 35, and to permit the springs 47, 47, 47, the frame 36, 36, 36, and the links 37, 37, 37 to reverse the swings to setting positions, as shown in broken lines, and the frames 36, 36, 36 to be moved into position as shown in 115 Fig. 26, where they are held until the tension on the springs 47, 47, 47 is released by another ascending movement of the elevator as hereinbefore described.

The cup *a* for the central pin A is mount- 130

ed on a swing similar in all particulars except the omission of the latch mechanism just described, and is connected with the opposite swing for the corner pins C by means of a connecting bar 55, as shown in Fig. 21, which is attached at its opposite ends to the parallel bars 31 of the two swings, thus simultaneously serving to move the central swing from its outermost position 10 on the filling line or circle to its innermost position A. Bar 55 is bent downwardly at the center and may be extended through suitable slots in the central ring or body of the elevator.

15 A tube a' is attached to and extends upwardly from the cage plate arm 22 to a point below the bottom of cup a and is provided with a flat top piece a^1 . A plunger a'' is slidably disposed in the tube and has a disk 20 a^2 on the top thereof upon which the lower flange of a spool a^3 is adapted to seat when the cup occupies a position thereabove, the lower end of the plunger being extended below cage plate 8 as in the case of the plungers for the cups b for engagement with the latch 28. When the cup a holds a pin the spool will be depressed in the cup and thus force the top disk a^2 and plunger downwardly for operating the latch.

30 Each of the corner cups c is also provided with a somewhat similar releasing device consisting of a pair of tubes c^1 attached to plate 8 of the cage and having a double plunger c' similar to those described in connection with cups b except that the tubes are not attached to the cups, and a spool c'' is supported in the cup for engagement with the upper end of the plunger for depressing the plunger when a pin reposes therein. The 40 spools of cups c are similar to that of cup a and the tubes c^1 are positioned on opposite sides of and permit the vertical movement of the elevator arm 24 therebetween, the spools serving as false bottoms for the cups 45 which are actuated by the weight of the pins.

50 The outer ends of arms 24 of the elevator are provided with recesses 56 having a height of about one half the height of the elevator arms and other recesses 57 are provided in the bottoms thereof to clear the swing pins 35, as shown in Fig. 21. At points equally distant from the center of the elevator ring and on lines radially disposed and cutting the pin positions B thereabove, the ring or 55 body portion 23 of the elevator is provided with a plurality of bushings 58 which may be entirely seated in the ring as shown, there being one of such bushings for each of the concentric pins, or six in all. A similar bushing is also provided in a lug 59 extending inwardly from the elevator body, as shown in Fig. 4, which is spaced from the central pin position A equally with those in the ring from the positions B, and one of 60 65 such bushings is also provided in each of the

arms 24 of the elevator and is spaced from the positions C equally with the others, there being one of such bushings for each of the ten pins. A pin lifter 60 is provided for each position which comprises an elongated 70 and vertically disposed rod 60' adapted to seat in a suitable bore in the cage plate 8 immediately below the pin positions, a relatively larger but shorter tube 60'' adapted to seat at the lower end in a bore in plate 8 and at its upper end in arm 24 and bushing 58 seated therein, and a horizontal plate or bar 61 attached to the rod 60 and tube 60'', as shown in Fig. 32 in detail. The bottom and upper ends of the rod and tube in each 80 lifter are beveled so as to cause them to readily seat in their respective bores in the plate 8 and the arms 24.

Means is provided in each of the bushings 85 58 for locking the lifters to the elevator so that they may be raised with the elevator and such means consists preferably of a ball 62 seated in a bore 63 which is closed by means of a plug 64, or otherwise, the ball being arranged to engage the periphery of 90 the tube 60'' (see Fig. 32) so that when the elevator is raised the engagement of the ball with the tube will cause the lifter to be bodily lifted therewith in the event that a pin is to be elevated at this particular position, 95 but in the event that a pin already occupies a certain position on the floor, I provide means for releasing the ball from engagement with the tube 60'' so that the lifter for such position may remain in the cage while 100 the elevator with other lifters ascends. It will be understood in this connection that frequently only a few of the pins are knocked down and in such case it is unnecessary to set such pins over again and it is 105 therefore desired to obviate this unnecessary effort.

As shown in Figs. 6, 8, 9 and 10, an electro-magnet selector 65 is provided for each pin position, all of these magnets being 110 mounted on the skeleton frame or base 29 as shown. Each magnet has a bell crank 66 pivoted thereto with an armature 67 and a horizontal arm 68 which extends to a point below the bushing 58 in the elevator. The end of the arm 68, in each case, is curved so as to permit the ready passage thereover of a plunger 69 which is slidably seated in the elevation and the upper end of which contacts with the ball 62 of the bushing, so that 115 when the magnet is energized and the armature retracted, the arms 68 will move upwardly and force the plunger and ball upwardly, thus releasing the lock from and permitting the ascent of the elevator without 120 the lifter. The operation of the selector magnet is accomplished by closing an electric circuit in each of the openings 5 of the frame 4 when a pin rests thereabove. Such means is disclosed in Figs. 40 to 45 inclusive. 130

Each of the openings 5 of the frame has a pair of trap doors 70, each being semi-circular in form, which are hinged by means of hinges 71 to opposite sides of the frame 4 adjacent to the openings. These doors are beveled as shown on their lower surfaces and rest on the beveled surfaces or edges of the walls around the openings. The doors are adapted to be raised upwardly by and for 10 permitting the passage of the pins through the openings 5, as clearly shown, but can not move downwardly below the level of the floor 2. As shown particularly in Fig. 45, a wire or plate 72 is seated in a groove in the 15 bottom of one or both of the doors in each opening and has its ends bent up over the beveled surface of the door adjacent to the inner periphery of the opening in each case. A screw 73 is insulated from and attached to 20 the wall of the opening at opposite points in each case and projects inwardly for contact with the end of the wire 72. A spring 74 acting upon the hinge 71 serves to normally hold the door with the contact wire therein 25 slightly above the level of the floor 2 when no pin is seated thereon, but when a pin is deposited thereon the weight of the pin will force the doors down to a level with the floor 2 and close the circuit of the magnet in 30 each case by causing the close contact of the screws 73 with wires 72, so that the selector magnets may operate to prevent the ascent of a lifter therebelow for elevating another pin to such position.

35 The pins are elevated by means of the rods 60' of the lifters, which, as the elevator ascends, enter bores 75 in the bottoms of the pins, as shown in Fig. 40 and carry the pins upwardly with the elevator, the beveled upper ends of the rods 60' readily engaging 40 the pins and suitable slots 76, Fig. 25, being provided in the cups *a*, *b* and *c* for each set of pins to permit the passage of the rods 60' and the horizontal portions 61 of the lifters 45 therethrough. The pins are elevated sufficiently above the level of the floor 2 and the trap doors so as to permit the doors to fall into normal or closed positions before the pins are dropped thereupon, the rods 60' in 50 such case descending with the elevator through a central aperture 77 formed at the joint of the doors and thus leaving the pin setting in the proper position on the door.

I will next describe the means of imparting power to the various elements hereinbefore dealt with together with other essential elements of structure and details included in my invention.

As shown in Fig. 2, the driving mechanism is mounted on suitable frame work including a plurality of vertical posts 78 aligned crosswise of the alleys and at the front end of the pin positions. Brackets 79 having adjustable bearings 80 and 81 mounted thereon carry, respectively, a line shaft

82 and a parallel counter shaft 83, a motor 84 being belted or otherwise connected with the line shaft 82, as shown in Fig. 12, for continuous operation. Motion may be communicated to the counter shaft 83 from the 70 line shaft 82 by means of gears 85 and 86 on shafts 82 and 83, respectively, and a clutch composed of a member 87 connected with the gear 85 on shaft 82, Figs. 51 and 52, said member and said gear being loose on said 75 shaft, and a positively driven member 88 adapted to mesh therewith. The means for actuating said clutch will be hereinafter described.

An auxiliary shaft 89, to the left hand side of the machine, is supported in parallelism with shafts 82 and 83 and carries a differential mechanism composed of a central pulley 90 and a multiple grooved sheave, as at 91 and 92, on opposite sides of said 85 pulley, all of said elements being loosely held on shaft 89. Shaft 89 may be supported in one or more clamps 93 attached to posts 78. Pulley 90 has a belt 90' of fabric or other material attached thereto at one end 90 and the other end thereof is suitably attached to a relatively smaller pulley 94 on shaft 83, as shown in Fig. 46. Pulley 90 has a relatively small sheave 95 mounted within the periphery thereof and adapted to 95 operate in a plane at right angles to that of the pulley, and said sheave is connected with and serves to rotate sheaves 91 and 92 uniformly therewith by means of a cable 95' running over sheave 95 and over the innermost grooves 91' and 92' of sheaves 91 and 92, respectively, the ends of the cable being suitably attached to the grooves in the sheaves 91 and 92, as shown.

Pulley 94 is loosely held on shaft 83 by 105 means of a split clamp 96 which has an annular internal groove adapted to be engaged by a flange 96' on the pulley, as shown in Fig. 46, thus preventing a longitudinal movement of the pulley on the shaft out of 110 alinement with the larger pulley 90, and the opposite end of pulley 94 has a clutch element 97 formed thereon. A sprocket 98 is also provided on shaft 83 for driving a chain 115 98' which is adapted to communicate power to mechanism at the rear of the machine to be hereinafter described. Sprocket 98 is connected with a clutch element 99 on the side thereof adjacent the clutch element 97 by means similar to that employed for connecting pulley 94 and clamp 96, the clutch elements 97 and 99 being adapted to be engaged for transmitting motion to pulley 90. Clutch element 99 is keyed to and is thus 120 positively driven at all times when the shaft 125 83 is rotating, but when clutch elements 97 and 99 are in engagement sprocket 98 will be idle.

A pulley 100 is keyed to shaft 83 at opposite sides of the alley, as shown in Figs. 130

1, 2, 12, 13 and 46, and each of these pulleys in each of the alleys carries a belt 100' which operates over a similar pulley 101 at the rear end of the alley and is suitably supported on the frame of the alley. The belts 100' operate in suitable grooves in the floor of the ball and pin channels 102 formed in the alley floor on opposite sides of the movable floor section 2 and thus serve to convey the knocked down pins and used balls rearwardly to conveying means to be hereinafter described.

The hub of pulley 100 adjacent to sprocket 98 on shaft 83 has a clutch element 103 formed thereon for engagement with another clutch element 104 formed on sprocket 98, so that when these clutch elements are engaged the sprocket may be driven by pulley 100.

20 Referring now to Figs. 14, 46, 47 and 48, I will describe the means for raising and lowering the movable floor section 2 of the alley for disposing of the deadwood or knocked down pins after the completion of a play. The front portion of floor section 2 has a pair of depending bars 105 and 105' positioned beyond the path of the elevator cage and on opposite sides of the center of the cage which are pivotally attached at 25 their upper ends at 106 to the floor section 2 and the lower ends thereof extend downwardly to points near the base of the cage and are provided with clevises 106'. A cable 107 is attached at one end to the left 30 hand groove 107' in sheave 91 and the other end thereof runs downwardly and is attached to the clevis 106' on depending bar 105. A similar cable 108 is attached to the groove 108' of sheave 91 and operates over a 35 smaller horizontally disposed sheave 109 suitably attached to the upper frame work of the alley, thence horizontally below the floor of the alley and beyond the center thereof, over a vertically disposed sheave 40 109' mounted on the frame work, and thence downwardly where the opposite end is attached to clevis 106' on bar 105', the sheave 109' being braced at 110 in any suitable manner.

45 Cables 111 and 112 are similarly attached to the grooves 111' and 112' of sheave 92 and extend horizontally below the level of the alley floor to the rear of the cage, as shown in Fig. 2, at which point the cables are separated and cable 111 runs downwardly and is attached to clevis 106' on the lower end of a tube 113 which is slidably held on a vertical rod 113' secured at its lower end in a metal base member 114, and the upper end 50 of 113 is loosely engaged by a depending stem 114' which is pivotally attached to the lower side of the movable floor section 2, a shoulder being provided on the stem against which the upper end of the tube 113 operates. The other cable 112 operates over a

55 horizontal sheave 115 and a vertical sheave 115' and runs downwardly at a point beyond the path of the cage where it is connected with a clevis 106' on the lower end of a tube 116 mounted on a rod 116' in a manner similar to tube 113 and rod 113' and also similarly connected with the opposite side of the floor section 2. Tubes 113 and 116 may have suitable guides at their upper 60 ends so as to insure a true vertical movement thereof.

70 The outer grooves 117 and 117' respectively, on sheaves 91 and 92 have cables 118 and 118' attached thereto which extend downwardly and carry weights 119 on the lower ends thereof, as shown in Fig. 12, for holding all of said cables taut under normal conditions and when the sheaves and pulleys are idle.

75 The outer side of the sheave 92 has a lug 119' formed thereon which is adapted to engage a plate 120 attached to the adjacent side of post 78 for stopping the rotation of sheave 92 at the proper time, and the inner side of sheave 91 has a lug 121' formed 80 thereon which is adapted to be engaged by a similar lug 121 on the adjacent side of pulley 90, as shown in Fig. 46, so that when power is applied to pulley 90, sheave 91 may be driven also by the engagement of 85 these lugs.

90 Thus, when power is applied to shaft 83 by means of the clutch means described, and from thence to pulley 94 on shaft 83 by means of the sliding clutch 97-99, the belt 90' on pulley 94 and connected with pulley 90, will unwind from pulley 90 on to pulley 94, thus rotating pulley 90 and sheaves 91 and 92 by means of the differentially connected cable 95' operating over 95 small sheave 95 and groove 91' and 92' until the lug 119' on sheave 92 engages plate 120 on post 78, at which time the rotation of sheave 92 is stopped, the cables 107 and 108 attached to bars 105 and 105', respectively, having in this operation raised the front 100 end of floor 2 to the level of the broken lines shown in Fig. 14, and cables 111 and 112 connected with tubes 113 and 116 having 105 similarly raised the rear end of the floor to the same level and slightly above the tops of whatever pins may remain in erect positions on the trap doors of the alley frame 4. The rotation of sheave 91 is accomplished thus far by means of the engagement of the lug 121' on sheave 91 with the lug 121 on pulley 90 and sheave 91 is further rotated at an accelerated speed by means of the differential cable and pulley 95, the front end of the floor section 2 being 110 substantially raised above the level of the rear end thereof, as shown in broken lines in Fig. 14, so that all of the pins which may have been knocked down and which remain on the floor section 2 may be dumped 115 120 125 130

therefrom into the rear portion of the alley for further disposition. The floor section 2 is then restored to normal position in the manner hereinafter described.

5 At the rear end of each of the alleys a ball and pin collecting and return mechanism is provided for automatically delivering the pins to the setting mechanism hereinbefore described and returning the balls 10 to the player's position. This mechanism is illustrated in Figs. 11, 17, 19 and 20 and comprises several individual yet coöperating elements which include a ball collector, a ball elevator and return system, a pin collector and inverter, a pin elevator and delivering means therefor to the setting means. The above elements will be described now in order.

20 The rear portion of the alley is completely padded to prevent damage to the pins and balls and that portion 122 immediately at the rear of movable floor 2 is inclined substantially and provided with a still lower portion 122' which communicates with a 25 ball collector composed of a pair of parallel rails 123 formed and spaced so that the balls may roll thereover but not drop therebetween, as shown in Fig. 11. These rails extend transversely of the alley. The rear 30 end portion 123' of the alley extends substantially forward over the tops of the balls 124 on the rails and thereabove a padded bumper 124' is pivotally supported at the top for receiving the impact of the balls 35 when forcibly thrown by the players. The various positions of the balls during their motion is indicated in Fig. 11 by broken lines, the balls being first in contact with the bumper 124', after which they roll 40 downwardly on the portion 122', thence on the rails 123 which are slightly inclined from one to the other side of the alley and thence to the end of the rails at the left hand side of the alley, which is preferably 45 the lowest. The mechanism which I am now about to describe is the same for each of the alleys, except that in one alley a right hand mechanism is provided while in the adjacent alley a left hand mechanism is employed.

50 The rails 123 for the balls, therefore, will be inclined downwardly from opposite sides of adjacent alleys so that the balls from the two alleys may be deposited in a common 55 elevator positioned midway between the two alleys. This elevator comprises a sprocket chain 125 operating over sprockets 126 at the bottom of the pit below the alley floor, and 126' above the floor, and a pair or more 60 of sets of rollers 127 suitably attached to the chain on opposite sides of the center for engagement with the balls. (See Fig. 20.)

Angle iron guides 128 are provided for each of the rollers 127 and they extend from 65 the level of the rails 123 upwardly to a

point above the center of the upper sprocket 126' and are curved around this sprocket and the chain, as shown, to guide the rollers therearound. The rear of the elevator comprises a vertical post 128' with ball guides 70 128 attached to the front side thereof and substantially spaced apart as shown, so that the balls 124 may be guided upwardly and firmly held between the rollers 127 and the stationary guides 128a, the balls being rolled 75 upwardly over the guides by means of the rollers 127.

The ball return consists of a pair of inclined rails 129 supported above the level of the alley floor on brackets 129' at suitable 80 intervals and curved upwardly at the rear end of the alley to the uppermost level of the ball elevator, as shown in Fig. 20, for receiving the balls delivered by the elevator and returning the same by gravity to the 85 player's position at the front end of the alley. One such return means is provided between each pair of alleys and is common to both of such alleys. The intervening junctions of the adjacent alleys have vertical partitions 130 extending slightly above the floor level so as to properly divide the alleys and prevent the balls from one alley entering another adjacent alley.

90 The ball conveyer sprocket 126' at the top of the elevator is mounted on a transverse shaft 131 which is supported at opposite ends in suitable bearings 131' held on brackets 132 from posts 128.

95 Lower ball elevator sprocket 126 is attached to a transverse shaft 133 journaled in frame members 134 and 134' on opposite sides of the ball elevator, said frame members being supported on beams 135 extended from the rear wall of the alley. 100 Somewhat similar frame members 136 are supported on similar beams at opposite sides of the alleys from the members 134 and 134' and are alined therewith. A pair of elongated rolls 137 and 137' are journaled at opposite ends and near the bottoms of the frame members 134 and 134' at one end in the members 136 at the other ends and have sprockets 138 and 138', respectively, attached thereto at their inner ends. 110

115 A similar pair of rolls 139 and 139', but which are smaller in diameter than those 137 and 137', are also journaled in the frame members at opposite ends and are parallel with the rolls 137 and 137' and 120 have sprockets 140 and 140' thereon at their inner ends. The sprocket chain 98' operating over sprocket 98, shown in Fig. 46, extends backwardly of the alley over and operates the sprockets 138 and 138' of the 125 rolls 137 and 137' and the sprockets 140 and 140' of the rolls 139 and 139', in the manner shown in Fig. 20, thus operating the first mentioned sprockets in a clockwise direction and the others in relatively 130

opposite directions to each other, one in a clockwise and the other in an anti-clockwise direction.

A ball clutch device is carried by each 5 of the ends of shaft 133 and comprises outer recessed members 142 having gear teeth 142' formed thereon and inner members 143 having peripheral recesses 143' formed therein. Balls 144 are held between the two members of each clutch, as shown in Fig. 34, and the outer members being loose on shaft 133 and the inner members being keyed thereon, the rotation of the outer members of the clutch in one direction causes the balls to wedge between 142 and 143 and to rotate the inner members and operate the elevator. The gears 142' mesh with gears 145 carried by the extended ends 141 of the forward rolls 137 so as to impart the proper motion to the ball elevator. Thus the common ball elevator for the two alleys may be operated by the mechanism of either of the alleys, the rolls 137, 137', 139 and 139' and their driving sprockets operating in different directions in each alley Figs. 11 and 17, and the ball clutches on shaft 133 being arranged so that they may actuate the shaft 133 in opposite directions according to the particular alley which may be operated.

The rolls 137, 137', 139 and 139' are provided with spiral elements 146 formed preferably of rubber or other resilient material and the lead of the spirals on each of the rolls is so arranged that the rotation of the rolls will serve to conduct the bowling pins which are dumped from the floor 2 to the rear portion 122 of the alley and permit the pins to fall between the rails 123 into position on the rolls of the pin conveyer, laterally of the alley, and also in such a manner that the pins may not be cramped between the rolls. For instance, if the spirals on rolls 137 and 137' lead in the same direction, or toward the right hand side of the alley, and the direction of rotation of said rolls is also the same, then the tops of the pins (which are smaller than the bottoms) will work downwardly between the rolls, as shown in Fig. 17, and the lead of the spirals thereon will cause the bottom ends of the pins as they are moved by the conveyer to emerge from the rolls, bottom first in every case. Thus the pins are faced properly prior to the setting operation.

At the opposite side of the alley from the spiral pin conveyer and adjacent to the end thereof, I provide a longitudinal pin conveyer composed of a pair of spaced belts 147 and 147' operating in parallelism over pulleys 148 and 148' on a shaft 149 at the rear end of the alley and similar pulleys 150 and 150' on a shaft 151 forward of the pin conveyer. Shaft 149 is journaled in

brackets 152' supported on beams 152 extending from the rear wall and shaft 151 in bearings 153 supported on said beams and also at the inner end of the alley the shaft 151 is journaled in a bearing 154 supported on the beam 135 which forms a support for frame member 134 of the pin conveyer. Said shaft extends entirely across the alley and carries a sprocket 151' near the inner end thereof which is driven by 75 means of the sprocket chain 98' operating over the pin conveyer sprockets, as shown in Fig. 20, and drives the longitudinal pin conveyer belts 147 and 147'. In the exact center of the alley, I provide a sprocket 80 155 which is held on a suitable support below shaft 151 and is connected with a bevel gear 156 adapted to mesh with a similar gear 156' revoluble on shaft 151, and a chain 12' operably connects sprocket 155 85 with the cage operating sprocket 12 in the center of the cage mechanism, as hereinbefore described, for rotating the cage and raising the elevator for the pins.

Thus, the sprocket 155 will be driven 90 when the shaft 151 is rotated, and the rotation of this shaft is controlled by means of a clutch composed of an outer cone member 157 and an inner cone member 157', the member 157 being attached to gear 156' and 95 loosely held on shaft 151 while member 157' of the clutch is keyed to the shaft 151, and rotates constantly therewith. A spring 158 holds the clutch members normally disengaged and a yoke 159 pivoted to a bracket 100 159' engages an annular groove in the sliding clutch cone member 157' and is adapted to be actuated by an electro-magnet 160 which is also supported on said bracket and when energized serves to move the clutch 105 members into engagement. The connections of this magnet will be hereinafter described.

The mechanism employed for elevating the pins is substantially similar to the ball 110 elevator hereinbefore described in detail and consists of a pair of guide rails 161 suitably held in vertical position and inwardly curved at their upper ends, as shown in Fig. 19, an elevating chain 162 carrying rollers 163 115 thereon and operating over sprockets 164 and 164' at the bottom and top, respectively, said sprockets being suitably supported for operation in bracket bearings 165. The pins are delivered by the belts 147 and 147' endwise to the elevating means and rest upon transverse rails 166 until a pair of the rollers 163 approaches and contacts with the peripheries thereof, whereupon they are elevated and deposited upon a pair of transverse rails 167 disposed at an elevation slightly higher than the receiving cups of the setting mechanism, and the rails 167 are slightly inclined with their lower ends near the center of the alley, as shown in Fig. 17. 130

The elevating sprockets are driven by means of bevel gears 168 and 168' on the lower sprocket shaft 169 and the shaft 151, respectively.

5 The spaced relation of the conveyer belts 147 and 147' permits the small ends to turn downwardly similar to their positions between the conveyer rolls 137 and 137' and thus their heavier portions near their bottom toms are faced toward the pin elevator as shown.

The pins after having been elevated as described roll down the rails 167 to the inner ends of these rails where they are deposited 15 in a curved chute 168^a having a trough like contour of about the same dimensions as the body of a pin which is pivotally supported at a point below and to one side of the center between the rails on a bracket 168^b. A 20 weight 169^a is carried on an arm 169^b which may be suitably attached to the supporting arm 170 of the chute for holding the chute in the normal position shown in Fig. 11. The bracket 168^b is supported on beams 171, 25 which also support the rails 167. The chute 168^a is alined with the longitudinal center of the alley so that when one of the pin receiving cups, *a*, *b* or *c* of the cage is brought into alinement therewith, and the pin which is 30 held in the chute may be moved in the direction of the cage and downwardly from the chute into the cup. As shown in Fig. 11, the wall of the chute near the end of the rails 167 has an opening, or is cut away to conform to 35 the shape of the pins so that the pins may readily roll into the chute from the rails, and when the chute moves inwardly for discharging a pin, the rear wall 172 thereof moves into position before the end of the 40 rails 167 and prevents another pin from being discharged therefrom until the restoration of the chute to normal position, the weight 169^a serving to restore the chute.

Referring back to the hereinbefore described structure and operation of the means employed for controlling the rotation and stopping of the cage for filling the cups *a*, *b* and *c* of the setting mechanism, as shown in detail in Fig. 7, means may be provided, 45 as shown in Figs. 20^a and 20^b for preventing the discharge of a pin from the chute 168^a in the event that a pin is already in position in a cup which may be brought into alinement with the chute.

55 This mechanism comprises a modification of the latch 28, or rather of the support for the latch, in that in lieu of supporting the latch on a rigid base as shown in Fig. 7, I provide a hollow rocking base 173 which 60 may be suitably held on the skeleton base of the cage and arranged to move slightly transversely of and with the latch 28. A rod 174 is attached to the web portion or supporting arm 170 of the chute and depends therefrom 65 to a point in contact with the upper surface

of the rocking base 173 of the latch so that when the base 173 and rod 174 are in such relative positions, the chute will be inoperative, the base preventing the movement thereof, but when the base is rocked and thus moved below the rod, the latter may move downwardly and permit the forward movement of the chute for depositing a pin in a cup.

It will be recalled from the previous description that the end 28' of the latch 28 is normally raised so as to permit the engagement of the end of the latch arm with the stop pin depending from the cage plate 8, but when a pin is held in one of the cups just being brought into filling position opposite the chute, the weight of the pin depresses the latch by means of the plungers described. Now, the plunger in a cup being so depressed when approaching the latch 28 will engage 85 the end 28' thereof and cause the latch and its rocking base to move slightly in a transverse plane, thus moving the base 173 into engagement with and preventing the depression of the rod 174 on the chute. As just 90 previously described, such conditions prevent the discharge of a pin into one of the cups. However if the cup is empty, the plunger of this cup will be raised, the latch 28 will not be rocked by contact therewith 95 so as to prevent the operation of the chute 168^a and a pin can be discharged therefrom.

My improved mechanism is adapted to be operated, as stated, automatically, but it is essential that the several elements thereof 100 should be controlled for operation in proper sequence by manual effort, and for this purpose I provide a series of electro-mechanical devices for manual operation to impart motion to the several elements.

105 The primary operation of the machine is to impart motion to the mechanism for the "sweep," which operation cleans the floor of the alley of all balls and pins which may remain thereon after the completion of a 110 single play. This, as has been described, is accomplished by raising the floor 2 and dumping the pins therefrom into the rear portion of the alley by means of the operation of shaft 83, pulley 90 and sheaves 91 115 and 92.

The shaft 83 is driven by gears 85 and 86 and clutch members 87 and 88, and means for operating which members is shown in Figs. 49 to 53, inclusive, and includes an arm 120 175 having a yoke 175' on the upper end thereof and carrying a pair of rollers 176 for engagement with the annular groove 176' of the member 88 of the clutch. The lower end of this arm is pivotally held on a lug 125 177 of a bracket 178 which is suitably attached to and extended from post 78 and the central and enlarged portion 178' of the arm carries a pair of rollers 179 which extend inwardly from the body of the arm. 130

A triple pointed cam 180 is rotatably mounted on a pin 180' secured in the upper end of the lug 177 and has a hub 181, which projects through an opening 181' in the arm, 5 as shown in Fig. 51. A ratchet 182 is attached to the side of the cam on said pin and an arm 183 is pivoted on said pin and carries a pawl 184 thereon for engagement with said ratchet and for moving said 10 ratchet on its axis.

The cam 180 is provided with three "high" points as at 185 and intermediate curved portions 186, which are equally spaced around the periphery thereof and are adapted 15 to be engaged by the rollers 179 on arm 175. One of these rollers engages one of the high points 185, on the cam and the opposite roller engages the opposite curved portion 186 when the clutch member 88 is 20 at either extreme of action. The ratchet has six teeth and is adapted to be moved by the pawl 184 one-sixth of a revolution at each operation, thus causing the cam to move correspondingly and each action of the 25 ratchet serving to reverse the previous position of the arm 175 and the clutch 88 with which the same is connected by means of the yoke 175', for it will be obvious that a movement of the cam and ratchet will disengage 30 one of the rollers from either a high or low point on the cam and move the same into engagement with either a low or high point, or vice versa, thus permitting a single operation of the arm 175 and a single direction 35 of movement of the cam to completely reverse the position of the clutch positively.

An electro-magnet 187 is supported on lugs 187' of the bracket 178 and has pivoted thereto a bell crank 188 between lugs 188', 40 the lower arm 188'' of which serves as an armature for the magnet and the upper arm 189 being connected with the pawl carrying member 183 by means of a link 189'. Thus, when the magnet is energized, the armature is attracted toward the core of the magnet and the bell crank arm 189 moves the ratchet arm 183 and the pawl 184 for operating the ratchet 182, as described. One 45 movement of the ratchet engages and succeeding movement thereof disengages the clutch members 87 and 88, and consequently either stops or imparts motion to the shaft 83.

The shaft 83 being rotated, motion may be communicated from the pulleys 100 thereon 55 to sprocket 98 by the engagement of the clutch members 103 and 104 for operating the ball and pin conveying mechanism hereinbefore described by means of chain 98', or, motion may be communicated to pulley 90 60 and sheaves 91 and 92 by the engagement of clutch members 97 and 99. Electrical means is also provided for actuating both of said clutches and includes a magnet 190 which is suitably supported on a bracket 190' carried 65 by one of the posts 78. An armature 191 is

attached to a pin 191' pivoted at the bottom in the bracket 190', a lever 192 is also attached to said pin above said armature, and a clutch operating yoke 193 is attached to the upper end of said pin above said lever 70 and the arms thereof engage the annular groove 194 of clutch 99 which is intermediate of clutch members 97 and 103 on shaft 83. Thus the energizing of the magnet 190 will attract the armature 191, move the lever 192 in the direction of clutch member 97 75 and engage clutch members 97 and 99 by means of the movement of yoke 193 simultaneously therewith. After the floor 2 has been raised and again lowered the clutch 80 members 97 and 99 may be disengaged and the members 103 and 104 engaged by means of a cam 195 formed on the outer face of the sheave 91, as shown in Fig. 54, which engages a roller 196 pivoted to the free end of 85 lever 192 and thus start the ball and pin conveying mechanism for disposing of the pins and balls dumped from the floor in the sweeping operation.

As shown in Figs. 37 and 38, means is provided for controlling the application of power from shaft 151 to the cage rotating elements through the medium of sprocket chain 12' operating over sprocket 12 at the bottom of the cage. This mechanism is of 90 95 the nature of a magnetic switch having certain novel mechanical features and characteristics which I will now describe in detail.

At a convenient point on the skeleton frame 29 below the cage is arranged a sliding contact mechanism composed of a 100 sliding base 197 which is suitably held on the frame 29 and has a contact plate 198 held thereon at the bottom and insulated from the bottom plate thereof by means of a suitable insulating piece 199. A pair of contact springs 200 and 201 are attached to plate 198 at one of their ends and the free ends thereof extend upwardly and outwardly as shown for selective contact with 105 three plates 202, 203, 204, which are supported on an insulating piece 205 attached thereabove to the top edge of a stationary plate 206 attached to frame 29. These upper contact plates are spaced apart and the 110 plate at the end of the top, or 204, is substantially longer than the plates 202 and 203, as shown. The plates 202, 203 and 204 have terminals 207, 208 and 209, respectively, attached thereto for connection with 115 the electrical system of my mechanism shown in the circuit diagram to be herein-after described.

The inner end 210 of base 197 is within 120 the range of the arms 20 of the cage plate 8, on which the pin-swings are mounted and the upper edge of the base end is slightly higher than the pins 38' of the swing bars 31 of the swings. A latch 211 is pivotally supported on base 197 intermediate of the 125 130

end 210 thereof and the contact plates thereon and is resiliently held upwardly by means of the tension of a flat spring 212, which is attached to the base 197 and acts upon the 5 lower side of the latch.

As shown in the drawings (Figs. 37 and 38) the swing is in setting position, pin 38' on bar 31 thereof is in engagement with a shoulder 213 on latch 211 and the base 197 10 has been previously moved to its extreme limit of action in the direction of the center of the cage and is so held by the latch, spring 200 is in contact with plate 202 and spring 201 is in contact with the inner end 15 of the longer plate 204. Now, a vertically slidable rod 214 is suitably mounted on the cage and operates through the upper and lower plates 7 and 8 thereof, the upper end of this rod being engaged by one end 215 20 of a lever 216 which is pivotally held near its center on plate 7. The elevator ring 23 has an upwardly extended pin or stud 217 which, when the elevator ascends to the uppermost limit of action engages the inner 25 end 218 of lever 216, thus lowering the opposite end of the lever and depressing the vertical rod 214 which has a horizontal extension 219 on the bottom below the cage plate 8 adapted to engage and depress the 30 latch 211. The depression of the latch will, as is obvious, release shoulder 213 thereon from engagement with pin 38' of the swing bar 31, whereupon the latch will move outwardly by means of a spring 220 attached 35 thereto and held in tension between the end thereof and a suitable projection of the frame 29. The outward movement, however, will be stopped by the engagement of the end 210 with pin 38', and when in such 40 position, spring 200 will occupy a position intermediate of the plates 202 and 203, thus breaking contact and opening the circuit. When the swing moves into filling position (which is at the opposite extreme 45 of action from that shown) the movement of pin 38' will permit the further outward movement of the base 197 until spring 200 contacts with plate 203, thus closing the circuit again.

50 The purpose of the above described mechanism is to control the application of power to the cage so that a minimum power may be applied when the swings and cups are in filling position and a maximum power 55 applied when the cage is in setting position; also for shutting off the power while the elevator is descending.

I will now describe the electrical connections by means of which the functions of 60 my system are carried out, reference being had to Fig. 58, in which a suitable number of battery cells 222 are connected and have a line circuit composed of positive wire 223 and negative wire 224 leading therefrom to 65 the various elements of the system.

Near the battery 222 the power clutch magnet 160, which has a primary winding 225 and a secondary winding 226, has a wire 227 connecting one end of coil 225 with negative wire 224 of the battery. The other 70 end of coil 225 leads to and connects with a contact plate 228 of the magnetic switch D, by means of wire 229. One end of secondary coil 226 is connected by means of wire 230 with the negative wire 224 of the 75 battery, and the other end thereof is connected by means of wire 231 with a wire 232 which leads to and is connected with terminal 208 of contact plate 203 on switch actuating base 197. Wire 232 is also connected with a switch plate 233 on switch D.

Terminal 209 of contact plate 204 is connected with positive wire 223 of the battery line by means of wire 233', and terminal 207 is connected with one end of switch coil 234 85 of switch D, by means of wire 235, the other end of this coil being connected with armature lever 236 of this switch which is adapted to make contact with plate 228. The armature 237 of switch coil 234 is connected 90 by means of wire 238 with terminal 239 of a manually operated switch E and the other terminal of this switch is connected by means of wire 240 with the negative battery wire 224.

The movement of the swing into setting position closes the circuit as far as the function of the controller 197 is concerned formed through plate 198, springs 200 and 201, terminals 207 and 209, wire 233' to 100 positive battery wire 223, wire 235, coil 234, switch D and switch E and their connections. But, in such position, the switch E will be open and the coil 234 deenergized. The closing of switch D energizes coil 234 105 and armature 237 being attracted by the magnet, contact is made between armature lever 236 and plate 228, thus energizing both the primary and secondary coils of the magnet 160 and imparting maximum power 110 to the line.

The movement of the base 197 by the completion of the ascent of the elevator 23, as previously described, opens the circuit at the controller switch base 197, spring 200 115 being in such event midway between terminal plates 202 and 203; but the complete reversal of the swing moves spring 200 into contact with plate 203, and the circuit is again closed, but the current is shunted 120 through wires 232 and 231, coil 226 of magnet 160, through battery 222, and wires 223 and 233' to terminal 209, plate 204, spring 201 and thence back to plate 198 of base 197, thus imparting to the cage only a minimum 125 power through coil 226 of the magnet 160.

The sweep switch F, which actuates the power clutch on shaft 83 for imparting motion to the floor elevating and inclining mechanism is connected at terminal 241 130

with one end of a coil 242 of a magnet G by means of wire 243 and the outer end of this coil is connected with positive battery wire 223 by means of wire 244. The opposite terminal of switch F is connected by means of wire 245 with negative battery wire 224, so that the closing of switch F will energize coil 242 and impart power to the sweep mechanism.

10 The starting switch H for shaft 83 has a magnet J connected with terminal 246 thereof by means of wire 247, the other end of this coil being connected by wire 248 with positive battery wire 223, while the negative battery wire 224 is connected with the other switch terminal by wire 249, so that the closing of this switch will energize the magnet J and either releases or imparts power to the shaft 83.

15 The selector magnets 65 for controlling the delivery of the pins by the setting mechanism are connected in multiple with the battery line, the connections of all of such magnets being essentially the same. Wires 250, 250, etc., lead from positive battery wires 223 to one end of the coils 251, 251, etc., while the other ends of these coils are connected by means of wires 252, 252, etc., with one of the pairs of screws 73 in the frame 4 opposite the trap doors at the playing positions of the pins. The other screws 73 are connected by wires 253, 253, etc., with negative battery wire 224, thus completing the circuit for energizing these magnets 65 when contact is made with the ends of the plates or wires 72 seated in the trap doors of the frame.

It will be understood from the consideration of the drawings and description of my improvements that it is my intention to provide a comprehensive system of bowling alleys, each of which is equipped with a single mechanism such as has been completely described. The several mechanisms, however, are coördinated and arranged for independent yet simultaneous operation, so that any one or more of the alleys, whether near or remote from each other, may be operated by a separate set of players without interference with each other.

The positioning of the ball return between the two units of each pair of alleys and above the level of the floor instead of on the level of the floor and between the alleys, conserves space and equally spaces all of the alleys, and the arrangement of the ball elevator and spiral pin conveyer as shown and described centrally relative to each pair of alleys economizes in the use of such mechanism and thus requires but half the number of units as would otherwise be required.

It has been found impractical in disclosing my improvements to completely illus-

trate all of the several elements in assembled views because of the complexity and intersecting planes of said elements, but it is confidently believed that the disclosure of such elements will be ample and sufficiently complete to enable those skilled in the art to thoroughly understand the structure and operation of the mechanism.

I am of the firm belief that I am the first to employ the novel and comprehensive means for handling the bowling apparatus herein disclosed and I desire to claim broadly thereon.

What I claim is:—

1. Bowling mechanism including assembling means for the pins, a movable floor 80 at the pin positions and means for elevating said pins in playing order through and depositing the same at the level of said floor.

2. Bowling mechanism including pin assembling means for collecting the pins in 85 concentric circles having a common center with the axis of the triangularly related pin positions, a movable floor at the pin positions, means for subsequently disposing said pins in triangular formation, and means 90 for elevating said pins to playing position.

3. Bowling mechanism comprising means for supporting the pins beneath the playing position in triangle formation for a play, 95 rotatable means for assembling said pins in circular formation about the axis of the triangle, and means for moving said pins into their respective triangularly related positions.

4. Bowling mechanism comprising a supporting frame for positioning the pins in 100 triangular formation for a play, a movable floor forming a covering for said frame and the spaces between and around said pins, means for assembling said pins below and elevating the same to the level of said floor, and means for raising and inclining said floor after a play for discharging the knocked down pins therefrom for another play.

5. Bowling mechanism including means for supporting a plurality of pins in 115 triangularly related playing positions, a floor section movable independently of the positioned pins of a set, and means for raising and inclining said floor section for discharging the reclining pins therefrom after a play.

6. Bowling mechanism including means for supporting a plurality of pins in 120 triangular relation for a play, a floor covering the region between and around said pins, and means for inclining said floor for discharging the reclining pins therefrom after a play.

7. Bowling mechanism including means for supporting a plurality of pins in triangular relation, a floor surrounding the

- pin positions and adapted to be raised to and inclined relative to a horizontal plane above the tops of such pins as may remain after the completion of a play for discharging therefrom the knocked down pins, and means for assembling and returning said latter pins to playing position for another play.
8. Bowling mechanism including means for supporting a plurality of pins in triangularly related playing positions, means for mechanically discharging the reclining pins from the alley after a play, and rotatable means beneath the plane of said alley for mechanically assembling and returning said pins to their respective positions for another play.
9. Bowling mechanism including means for supporting a plurality of pins in triangular position, means for disposing of the reclining pins resulting from a play without interfering with such pins as may remain erect on the alley, and rotatable means beneath the playing positions for automatically assembling and returning said other pins to their respective playing positions for another play.
10. Bowling mechanism including means for supporting the ten pins of a set in triangular formation, the central pin of the set being axially positioned relative to the triangle, six of said pins being concentrically arranged at equal intervals about the said central pin, and the three remaining pins forming the corners of the triangle and being concentric with said other pins, means for assembling all of said pins in the plane of the circle of said six pins, and means for subsequently moving said central and corner pins of the set from the assembling circle into their triangularly related positions.
11. Bowling mechanism including means for supporting a plurality of pins in triangular formation about the axis of a central pin, said pins being spaced at equal intervals and arranged in concentric circles about said central pin, means for assembling all of said pins after a play in a single circle concentric with the axis of the playing triangle, and means for thereafter moving said pins into their normal triangular positions.
12. Bowling mechanism including a plurality of pins arranged in triangular and concentric formation about a common axis, means for assembling all of said pins in a single circle concentric with said axis after a play, and means for thereafter positioning said pins in their normal triangular formation for another play.
13. Bowling mechanism including a plurality of pins arranged in triangular and concentric formation about a common axis, means for assembling said pins subsequent to a play in their triangular formation in a plane beneath the playing positions, and means for elevating said pins in such formation to their playing positions.
14. Bowling mechanism including a plurality of pins arranged in triangular and concentric formation about a common axis, means for disposing of the reclining pins after a play and for reassembling such pins in playing formation, and means for elevating said pins thereafter to their playing positions about the other pins.
15. Bowling mechanism including a plurality of pins arranged in triangular formation at the level of the alley floor, means for discharging the reclining pins resulting from a play to a point below the plane of said floor, means for reassembling such pins in playing formation, and means for elevating said pins thereafter to playing position.
16. Bowling mechanism including a plurality of pins supported in playing position at the level of the alley floor, a rotatable assembling element supported for operation below the plane of said pins, means for delivering the knocked down pins from said floor to said assembling element, and means for selectively collecting said pins in playing order and elevating the same to playing position.
17. Bowling mechanism including a plurality of pins supported in playing formation at the level of the alley floor, a rotatable assembling element operably supported below the plane of the playing positions of said pins, means thereon for selectively assembling the pins after a play, and means supported on said assembling element for elevating said pins to playing position.
18. Bowling mechanism including a plurality of pins supported in playing formation at the level of the alley floor, an assembling element disposed beneath the playing positions of said pins, and means supported on said assembling element for elevating said pins to playing position after the completion of the play.
19. Bowling mechanism including a plurality of pins supported in playing formation, assembling means disposed below the plane of said pin positions, and pin elevating means connected with said assembling means for raising said pins to playing position after the completion of a play.
20. Bowling mechanism including a plurality of pins supported in playing formation, a plurality of pin collecting and reassembling elements disposed below the plane of the pin positions, means for delivering said pins after the completion of a play to said assembling elements in selective order, and means for elevating said pins to playing position for another play.

21. Bowling mechanism including a plurality of pins arranged in playing formation, rotatable assembling and elevating means disposed beneath the playing positions for restoring said pins to normal positions after a play, and means controlled by the presence of one or more of said pins in their playing positions whereby other pins may not be assembled and elevated to such positions for a subsequent play. 10
22. Bowling mechanism including a plurality of pins arranged in playing formation, rotatable assembling and elevating means disposed beneath the playing positions for restoring said pins to playing positions, after a play, and means whereby when certain of the pin positions are occupied other pins may be prevented from being delivered thereto. 15
23. Bowling mechanism including a plurality of pins arranged in playing formation in a common plane, pin assembling and elevating means disposed below said plane and for restoring the pins to playing positions after the completion of a play, means for facing and delivering said pins to said assembling means, and means for selectively actuating said assembling means for controlling the delivery of but a single pin to any one of the pin positions. 20
24. Bowling mechanism including a plurality of pins arranged in playing formation and pin assembling means therefor, pin conveying means connected therewith for facing and delivering said pins after a play to said assembling means, a ball collector and conveyer means for returning the balls to playing position, and means whereby said ball collector and conveyer may be independently actuated for serving two adjacent bowling alleys. 25
25. Bowling mechanism including a plurality of pins arranged in playing formation, rotatable pin assembling and elevating means therefor, pin facing and conveying means connected therewith for delivering the pins after a play to said assembling means, means for selectively actuating said pin delivery to said assembling means for preventing the delivery of but a single pin to a single position, and means for collecting and returning the used balls in a play to their normal playing position. 30
26. In a bowling mechanism comprising an alley for supporting a plurality of pins in playing formation, pin assembling and elevating means therebelow for raising the pins through the alley floor to playing position after a play, means for facing and delivering the pins to said assembling means, and means for returning the used balls to playing position. 35
27. In a bowling mechanism, an alley having channels on opposite sides thereof for conducting the balls and pins to the rear end thereof for subsequent use, a plurality of said pins thereon in playing formation, a conveyer belt operating in each of said channels for insuring the dispositon of said pins after a play, and automatically actuated means for collecting and reassembling said pins and balls at the playing positions. 40
28. In a bowling alley having a plurality of pin positions at one end thereof and pins for said positions, a channel on each side of said pin positions, a conveyer in each of said channels for discharging the reclining pins therefrom, pin and ball collecting and reassembling means below the plane of said pin positions, and means for elevating and restoring said pins and said balls to playing positions for another play. 45
29. A multiple unit bowling mechanism comprising a plurality of units having a common operating means, independently operable pin conveying and reassembling means in each of said units, and a common ball restoring means for each pair of said units. 50
30. A bowling mechanism comprising a plurality of alley units arranged in succession, common operating means for all of said units, independently operable pin conveying, reassembling and elevating means for each of said units for restoring the pins to playing position after a play, and common ball restoring means for and positioned between each pair of units and operable by and with either and both units of a pair, as set forth. 55
31. A bowling mechanism comprising pin supporting, collecting and rotatable reassembling means, ball collecting and restoring means, a driving element therefor, and means for controlling the application of power from said driving element to each of said means in the order of their desired operation. 60
32. A bowling mechanism comprising, pin supporting, conveying and reassembling means disposed below the playing positions of the pins, ball returning means, a driving element therefor, and electro-magnetic means for controlling the application of power from said driving means independently and selectively to each of said other means. 65
33. A bowling mechanism having rotatable means for assembling and elevating the pins to playing positions after a play and ball returning means, driving means therefor, electro-magnetic means for independently applying power from said driving means to said other means, and a system of electrical connections including switches for manually controlling the operation of said electro-magnetic means. 70
34. A bowling mechanism for a plurality of alleys and having independent pin conveying means, rotatable assembling means and elevating means in each alley, a com- 75

- mon driving means for all of said alleys, electro-magnetic means for selectively controlling the application of power from said driving means to said other means in each 5 alley, and a series of electrical connections in each alley including electrical switches for manually controlling the operation of said electro-magnetic means.
35. A bowling mechanism comprising adjacent sets of pin conveying means, rotatable assembling means and elevating means having a common driving means and capable of independent connection therewith for selective operation, a ball returning mechanism for each pair of units, and means for controlling the application of power to each of said units, including a series of electrical and mechanical connections operable from the players' positions for controlling 10 the operation of all of said units.
36. A bowling mechanism including removable trap doors for holding the pins in playing positions, and a floor section for receiving the deadwood after a play, said 15 floor section being tiltable for discharging said deadwood to points exterior of the playing triangle.
37. A bowling mechanism including means for supporting the pins in playing position, 20 and a vertically movable and tiltable floor thereabove, for receiving and discharging the deadwood after a play.
38. In a bowling mechanism, means for supporting the pins in playing formation, a 25 floor section for receiving the deadwood after the completion of a play, and means for elevating and tilting said floor section, for discharging said deadwood to points exterior of the playing triangle.
40. 39. A bowling mechanism including a stationary frame for supporting the pins in playing formation, a floor normally supported substantially flush with the bottoms of the pins for receiving the deadwood after 45 each play, and means for elevating said floor to a plane above the tops of the erect pins after the completion of a play.
40. A bowling mechanism including trap doors for supporting the pins in playing 50 formation, a floor for holding the deadwood after a play, and means for tilting said floor for discharging said deadwood.
41. A bowling mechanism including means for supporting the pins in playing formation, a floor for holding the deadwood after 55 a play, and means for initially elevating and finally tilting said floor to clear the remaining erect pins, for discharging the deadwood therefrom.
60. 42. In a bowling mechanism, pivoted pin supporting means, and a movable floor at the playing position adapted to hold and discharge the deadwood after a play without disturbing the remaining erect pins.
65. 43. A bowling mechanism including a
- frame at the playing position having a plurality of openings therein, pivoted closures for said openings, means for elevating the pins through said openings, said pins when so elevated being adapted to seat upon said 70 closures.
44. A bowling mechanism including a frame at the playing position having a plurality of pivotally movable pin seats supported thereon in playing formation, and 75 arranged so as to permit the elevation of the pins through said frame.
45. A bowling mechanism including a frame at the playing position, pivotally movable pin seats supported thereon, and 80 means for elevating and depositing the pins on said seats.
46. A bowling mechanism including a plurality of pin supports arranged in playing formation at the level of the alley floor, 85 means for elevating and depositing the pins upon said seats, a floor surrounding said seats, and means for moving said floor for discharging the deadwood therefrom.
47. A bowling mechanism including a 90 plurality of pivoted pin supports, a floor surrounding said supports, means for elevating the pins above the level of and depositing the same upon said supports, and means for elevating and tilting said floor 95 for discharging the deadwood therefrom.
48. A bowling mechanism including means for supporting the pins in playing formation, a rotatable pin receiving mechanism below the playing position, and an elevator 100 rotatable with said mechanism and adapted to raise the pins to playing positions.
49. A bowling mechanism including, a rotatable cage supported below the playing position of the alley and provided with an 105 elevator for receiving and raising the pins to the playing position.
50. A bowling mechanism including a rotatable pin assembling mechanism supported below the plane of the alley and having an 110 elevator for raising the pins to playing position, and means for delivering said pins to said elevator.
51. A bowling mechanism including an 115 alley floor, a rotatable pin receiving element, a pin elevator rotatable therewith, for elevating the pins through said floor to playing position, and means for delivering said pins from said floor to said receiving element.
52. A bowling mechanism including a rotatable pin assembling element below the plane of the alley floor, an elevator rotatable therewith for raising the pins to the level of said floor, and means for delivering the 125 pins, successively, to said assembling element and to said elevator.
53. A bowling mechanism including an 130 alley floor, an assembling mechanism having a rotatable base provided with a plu-

rality of pin receiving and holding swings movable relative to the playing position, for moving the pins from a common point into playing formation.

5 54. A bowling mechanism including an assembling mechanism having a rotatable base concentrically supported relative to the playing position and formation and provided with a plurality of swings for receiving the pins at a common point of delivery and moving the same into positions beneath their respective playing positions.

55. In a bowling mechanism, an alley floor, pin supporting means for a play, means for discharging the deadwood from playing position to a point below the level of said floor, means below said floor for collecting and facing said pins, means for elevating said pins to a common point of discharge, and rotatable means for receiving the pins at the point of discharge and elevating the same to playing position.

56. A bowling mechanism including an alley floor, means for discharging the deadwood from said floor to a point therebelow, rotatable assembling means below said floor and concentrically relative to the center of the playing triangle, means for delivering said pins to said assembling means, means

for elevating said pins to playing position, 30 and means for supporting said pins in playing formation.

57. A bowling mechanism including a trap for receiving the deadwood and spent balls after a play, means for permitting the passage of the pins through said trap, means for elevating said pins through the alley floor playing position, and means for elevating to and returning said balls from said trap to the player's position. 40

58. A bowling mechanism including a pin collecting device comprising spaced pairs of parallel spiral rolls with openings therebetween for receiving and facing the pins after a play. 45

59. A bowling mechanism including a pin collecting device comprising vertically and horizontally spaced spiral rolls for receiving and conveying the pins after a play to a point of discharge, said rolls serving to 50 similarly face all pins in one direction.

Signed at Los Angeles, county of Los Angeles, and State of California, this 3d day of December, 1917.

OREN J. FAIRCHILD.
